UNITED STATES PATENT OFFICE.

CYRUS M. APPLEGET, OF NORTH YAKIMA, WASHINGTON.

MUSIC-LEAF TURNER.

1,256,423.

Specification of Letters Patent. Patented Feb. 12, 1918.

Application filed December 14, 1916. Serial No. 137,025.

To all whom it may concern:

Be it known that I, CYRUS M. APPLEGET, a citizen of the United States, residing at North Yakima, in the county of Yakima and State of Washington, have invented certain new and useful Improvements in Music-Leaf Turners; and I do hereby declare the following to be a full, clear, and exact description of the invention, such as will enable others skilled in the art to which it appertains to make and use the same.

This invention relates to music leaf turners and has for its principal object to provide a device of this character whereby the leaves of sheet music or music in book form may be turned consecutively from the right to the left while playing the music and embodying means whereby all of the leaves turned may be simultaneously turned to the right or to their original position.

Another object of the invention is to provide a device of this character embodying a plurality of music leaf turner arms that are detachably engaged with the turning mechanism.

A further object of the invention is to improve and simplify devices of this character so as to be of comparatively inexpensive construction, of durable and substantial design, and one which may be readily and quickly manipulated in an efficient manner.

With these and other objects in view as will appear as the description proceeds, the invention comprises the various novel features of construction, combination and arrangement of parts as will be more fully described hereinafter and set forth with particularity in the appended claims.

Referring to the drawings.

Figure 1 is a perspective view of my improved music leaf turner.

Fig. 2 is a vertical sectional view taken on the line 2—2 of Fig. 1.

Fig. 3 is a horizontal section taken on the line 3—3 of Fig. 2.

Similar characters of reference are used to denote like parts throughout the accompanying drawings.

Referring more particularly to the drawings, the reference numeral 1 indicates the base board of my improved music leaf turner, upon which is mounted a frame work 2 by screws or other suitable fastening means 3, this frame work being preferably located adjacent the bottom of the base board. This frame work 2 is provided at

the bottom portion thereof with a pair of downwardly and outwardly curved supporting arms 4, in the outer ends of which is supported and horizontally disposed a shaft 5 and upon which is pivotally mounted a plurality of substantially L shaped operating keys 6, the outwardly extending horizontal portion of these keys being provided with a finger piece 7 whereby they may be rocked upon the shaft 5 to operate the mechanism to be hereinafter described.

Extending upwardly from the upper part of the frame work 2 are a pair of arms 8, the upper ends of which are each provided with a socket 9 which is adapted to receive the lower tapered ends of a retaining bar 10, that is disposed vertically upon the base board and extends upwardly to a point adjacent the top thereof. These retaining bars 10 are arranged in substantially parallel relation to each other and are adapted to be positioned over the cover leaves or backs of the music that is positioned upon the base board 1 to be played, these bars being spaced apart sufficiently to permit the leaves of the music to extend upwardly therebetween in order that they may be grasped by the music leaf turner arms which will be presently described. The base board 1 is further provided with a pair of horizontally disposed shelves 11 which are positioned on the opposite sides of the sockets 9 carried by the arms 8.

Bearing brackets 12 and 13 project outwardly from the base board 1, and rotatably mounted in the bearing bracket 12 is the lower end of a vertically disposed shaft 14, which is provided with a bearing collar 15 adjacent its lower end that is designed to rest upon the lower bearing bracket 12. The lower end of the rotatable shaft 14 is provided with a grooved pulley 16 which is keyed or otherwise fixed thereto and rests upon the bearing collar 15 which latter also serves to space the grooved pulley from the bearing bracket. The upper end of the rotatable shaft 14 extends upwardly to a point beyond the bearing bracket 13 and has keyed thereto or otherwise fixed a circular head block 17, to the peripheral edge of which is attached a vertically extending substantially V shaped socket 18.

Surrounding the shaft 14 is a rotatable tubular shaft 19, the lower end of which rests upon the grooved pulley 16 and is provided adjacent this lower end with a grooved

pulley 20 which is securely fixed thereto, the upper end of said tubular shaft extending upwardly to a point adjacent the head block 17 so as to be in spaced relation thereto and 5 has fixed thereto a head block 21 similar to the head block 17, and is likewise provided with a substantially V shaped socket 22 which is of a length slightly greater than the socket 18.

10 Surrounding the tubular shaft 19 is a rotatable tubular shaft 23, the lower end of which rests upon the grooved pulley 20 and carries adjacent its lower end a grooved pulley 24 which is fixed to the tubular shaft for 15 rotation therewith. The upper end of this tubular shaft 23 is provided with a circular head block 25 that is fixed thereto and rests upon the upper surface of the bearing bracket 13, in which the tubular shaft 23 is 20 journaled for rotation. The peripheral edge of the circular head block 25 is also provided with a vertically V shaped socket 26 which is of a length slightly greater than the socket 22.

25 The device shown is constructed to turn three music leaves consecutively through the medium of the operating keys 27, 28 and 29 respectively, a key 30 being employed to reverse or move all of the leaves that have 30 been turned back to their original position simultaneously. The vertical extending portion of each of the substantially L shaped keys increases in height from the first to the third or last key, and as clearly shown, they 35 are each connected to their respective pulleys 16, 20 and 24 through the medium of cables 31, which extend half way around each of the grooved pulleys and are securely fastened thereto by a staple or any other 40 suitable fastening means 32. The lower cable 31 that extends around the grooved pulley 16 from the operating key 27 is extended around and beyond the pulley and has its terminal end connected to the upper 45 end 33 of the reverse key 30, whereby all of said circular head blocks may be rotated back to their original position after they have been once operated in the course of turning the music.

50 Detachably engaged with each of the sockets 18, 22 and 26 is a vertically extending music leaf turner bar 34, the lower end of which is tapered and is designed to wedgely engage within its respective socket. 55 These turner bars 34 have connected to them adjacent their lower ends and the upper ends of the sockets in which there are mounted horizontally extending music leaf turner arms 35, the outer ends of which may or may 60 not as desired be provided with spring clamping fingers between which the lower edges of the music leaves may be held while being turned from one position to another. The upper ends of each of the bars are 65 provided in one of their side edges with

a series of ratchet teeth 36 which are designed to be engaged by the inner beveled wall 37 of an operator arm 38, which is slidably positioned over the upper end of each of these turner arms. As shown, the arms 70 38 extend horizontally and have their outer free ends provided with spring clamps 39 which are designed to grip the outer edges of the music leaves.

By the particular construction of the inner ends of each of these arms 38 and the upper ends of the bars 34, it will be apparent that the arms can be adjusted vertically upon the bars 34 and held in such adjusted position through the medium of their own 80 weight. The base board 1 is further provided with bowed springs 40 securely attached at one end to the base board and positioned upon the opposite sides of the retaining bars 10, and it is to be understood 85 that these springs 40 are designed to press the music leaves outwardly against the music leaf turner bars and their respective arms and thus preventing the leaves from sagging in the middle.

90 In the operation of the device the music is placed upon the base board 1 and on the shelves 11 thereof and the retaining bars 10 are then positioned over the cover leaves of the music and engaged with the sockets 9 95 so as to be firmly held in position to retain these cover leaves upon the base board and at the same time permit the music leaves to extend outwardly between them into position to be engaged by the leaf turner arms. 100 The cover leaves having been positioned in fixed relation to the base board, the leaf turner bars 34, which each carry the arms 35 and 38 are each positioned over and attached to each succeeding leaf from the rear 105 cover leaf to the front cover leaf, after which their lower ends are engaged in the sockets 18, 22, and 26. The turner bars 34 having been arranged in position over each of the 110 music leaves, the device is now ready to operate in order to turn the leaves from the right to the left. When it is desired to turn the first sheet of music over, the key member 27 is depressed which will rotate the pulley 16 carried by the lower end of the rotatable 115 shaft 14, this movement rotating the head block 17 which carries the V-shaped socket 18 and in which is positioned the outermost or first of the turner bars 34, whereby it will be seen that the first leaf of music will be 120 moved from the right to the left. Likewise each successive sheet is turned from the right to the left by the depression of each succeeding key 28 and 29. Now in order to reverse the movement of the turner bars or 125 in other words to move the music leaves from the left to the right or their original position, the reverse key 30 is depressed which will rotate the grooved pulley 16 in a reverse direction to the direction in which 130

it was originally moved, which will rotate the socket 18 from the left to the right also moving the sockets 22 and 26 positioned upon it over to their original position.

5 It is to be understood that the weight of the arms 35 and 38 together with the bars 34 will be sufficient to retain the music leaves upon the right hand side of the device against the liability of being accidentally 10 turned through the medium of wind or any other means. However, should the weight of the bars and arms not be sufficient to hold the music leaves in position on the right side of the device, I propose to employ a series of 15 spring arms 41 that have their outer ends securely attached to the frame work 2, and their inner ends engaging behind lugs 42 formed on the upper surfaces of the grooved pulleys 16, 20 and 24, these spring arms 20 exert an outward tension behind the lugs 42, tending to urge the pulleys around to the right which in turn will cause the said turner bars to be firmly pressed to the right against the base board 1. When the operating 25 keys have been depressed and the music leaves turned to the left, the weight of the keys will serve in addition to the weight of the turner bars and arms to positively maintain them in turned position.

30 What I claim is:—

1. A music leaf turner, comprising a base board, a frame work mounted thereon, bearing brackets extending from the base block, a plurality of shafts telescopically mounted 35 in said bearing brackets, a grooved pulley carried by the lower end of each of said

shafts, a circular head block carried by the upper end of each of said shafts, a music leaf turner arm attached to each of said circular head blocks, a lug formed on each of 40 said grooved pulleys, spring arms attached to said frame work and engaging behind said lugs and adapted to urge said pulleys to the right to hold the music turner arms upon the music leaves, means for rotating 45 said pulleys consecutively in one direction, and means for rotating all of said pulleys simultaneously in the opposite direction.

2. A music leaf turner comprising a base board, a frame work mounted thereon, bearing brackets extending from the base block, a plurality of shafts telescopically mounted 50 in said bearing brackets a grooved pulley carried by the lower end of each of said shafts, a circular head block carried by the 55 upper end of each said shafts, a music leaf turner arm carried by each circular head block, a bracket projecting laterally from said frame work, a plurality of L-shaped operating keys pivotally mounted in said 60 bracket, and flexible elements connecting the upper ends of said L-shaped keys to said grooved pulleys whereby each of said music leaf turner arms may be consecutively and 65 simultaneously actuated.

In testimony whereof I have signed my name to this specification in the presence of two subscribing witnesses.

CYRUS M. APPLEGET.
